UNITED STATES PATENT OFFICE.

CHARLES DIMECH, OF WEST POINT, NEW YORK.

ROTARY STAMPING DEVICE.

1,205,168.

Specification of Letters Patent. Patented Nov. 21, 1916.

Application filed May 9, 1916. Serial No. 96,308.

To all whom it may concern:

Be it known that I, CHARLES DIMECH, a citizen of the United States, residing at West Point, in the county of Orange, State 5 of New York, have invented a new and useful Rotary Stamping Device; and I do hereby declare the following to be a full, clear, and exact description of the invention, such as will enable others skilled in the art to 10 which it appertains to make and use the same.

The present invention relates to a rotary stamping device, and has for its object to provide a device of this character which embodies novel features of construction whereby a number of printing surfaces, such as 15 rubber stamps, can be mounted upon the periphery of a drum and any selected one of the printing surfaces quickly inked and 20 brought into proper position for stamping.

Further objects of the invention are to provide a rotary stamping device which is simple and inexpensive in its construction, which admits of the printing surfaces being 25 quickly changed, which is very compact in its design, and which can be used without danger of soiling the fingers.

With these and other objects in view, the invention consists in certain novel combinations and arrangements of the parts as will 30 more fully appear as the description proceeds, the novel features thereof being pointed out in the appended claims.

For a full understanding of the invention, 35 reference is to be had to the following description and accompanying drawing, in which:—

Figure 1 is a side elevation of a rotary stamping device constructed in accordance 40 with the invention, the stamping drum and indicating pointer being shown in their normal positions. Fig. 2 is a view similar to Fig. 1, showing the indicating pointer in the position assumed preparatory to rotating a selected stamping block into operative 45 position. Fig. 3 is an end elevation of the device as shown by Fig. 1. Fig. 4 is a vertical longitudinal sectional view through the stamping drum. Fig. 5 is a detail perspective view of one of the metal clips for receiving the stamping blocks.

Corresponding and like parts are referred to in the following description and indicated in all the views of the drawings by the same 55 reference characters.

Specifically describing the present embodiment of the invention, the numeral 1 designates a stamping base which is provided at one end thereof with a standard 2. Corresponding levers 3 are pivotally mounted at 60 points spaced from the rear ends thereof, as indicated at 4, upon opposite sides of the standard 2. The rear ends of the levers 3 are connected to springs 5 which normally tend to swing the forward ends of the levers 65 upward and lift the printing drum away from the stamping base 1. The extremities of the levers 3 are extended downwardly at 3^a and connected by a shaft 7 which has the printing drum 6 rigidly mounted thereon. 70

A fork 8 straddles the printing drum 6 and has the arms thereof pivotally mounted upon the shaft 7, the arched end of the fork being provided with a handle 9, while the arms thereof terminate at their free ends in 75 resilient pointers 10 which are used to indicate which one of the printing surfaces on the periphery of the drum is in operative position. One end of the shaft 7 terminates in a wing or finger piece 11 by means of 80 which the shaft and drum can be rotated to bring any selected one of the printing surfaces into operative position. The opposite end of the shaft 7 terminates in a head 12, and a spring 13 is interposed between the 85 said head and the adjacent lever 3, thereby causing the ends of the printing drum 6 to be frictionally gripped by the fork 8. By grasping the handle 9 of the fork 8 and forcibly rotating the printing drum 6 90 through the medium of the finger piece 11, any selected one of the printing surfaces on the periphery of the drum can be brought into operative position, and the frictional engagement between the fork and the drum 95 is ordinarily sufficient to hold the parts against accidental displacement.

The periphery of the printing drum 6 is provided with a series of longitudinally extending undercut or dovetail grooves or recesses 14. Correspondingly shaped sheet metal clips 15 are adapted to be slipped removably into the recesses 14, and these clips 15 are designed to carry blocks 16 upon which the printing surfaces 17 are mounted. 100 These blocks 16 are interchangeable and removable, so that the printing surfaces carried by the drum 6 can be changed as often as desired. One end of the drum may be provided with a pair of spaced projections 110 or knobs 18 opposite the base of each of the dove-tail recesses 14. The resilient pointer

10 of the fork 8 will ride over the projections 18 when the drum 6 is forcibly rotated through the medium of the finger piece 11, although when any particular one of the 5 printing surfaces is brought into operative position, the spring pointer will seat itself between the corresponding pair of projections 18, thereby locking the fork and drum against relative rotation.

10 An inking roller 19 is journaled between a pair of arms 20 which project forwardly from the upper end of the standard 2, and the springs 5 normally operate upon the levers 3 to swing the printing drum 6 upwardly toward the inking roller.

15 When it is desired to use the stamp, a selected one of the printing surfaces 17 is rotated into position opposite the pointers 10 of the fork 8. The handle 9 is then 20 swung downwardly and forwardly to bring the printing surface into engagement with the inking roller 19, after which the handle 9 is swung upwardly to bring the fork 8 into a substantially vertical position with 25 the selected printing surface properly inked and at the bottom of the printing drum. The paper or article to be stamped may be inserted between the drum 6 and base 1, and the printing surface brought into engagement therewith by pressing downwardly on 30 the handle 9. As soon as this pressure upon the handle 9 is released, the springs 13 will again lift the printing drum into inoperative position, whereupon the paper or other 35 article which was stamped can be removed. This operation can be very quickly repeated, as often as desired, and it will be obvious that any desired one of the printing surfaces 17 can be very readily brought into 40 proper position for use. If desired, the pointers 10 may carry counter-weights 21 for causing the fork 8 to automatically assume an upright or vertical position as soon as released.

45 Having thus described the invention, what I claim as new and desire to secure by Letters Patent, is:—

1. A rotary stamping device, including a base plate, a standard, a pair of levers pivotally mounted upon the standard, a printing drum journaled between the levers, a series of independent printing surfaces mounted on the periphery of the drum, a fork straddling the drum and adapted to 50 grip the ends thereof at adjusted positions, a handle on the fork for swinging the printing drum toward the base plate, and inking means.

60 2. A rotary stamping device, including a base plate, a standard, an inking roller carried by the standard, a pair of levers pivotally mounted upon the standard, a printing drum journaled between the levers, a series of independent printing surfaces 65 mounted on the periphery of the drum,

yielding means acting upon the levers for moving the printing drum away from the base plate and toward the inking roller, a fork straddling the printing drum and adapted to grip the ends thereof at adjusted positions, and a handle upon the fork for rotating the drum to ink a selected printing surface and then bring it into printing position over the base plate.

3. A rotary stamping device, including a 75 base plate, a standard, a pair of levers pivotally mounted upon the standard, a shaft connecting the levers, a printing drum upon the shaft, a series of independent printing surfaces mounted on the periphery of the 80 drum, a fork mounted upon the shaft and straddling the drum, a spring for forcing the fork into a frictional engagement with the ends of the drum, inking means, and a handle on the fork for swinging the printing 85 drum toward the base plate.

4. A rotary stamping device, including a base plate, a standard, a pair of levers pivotally mounted upon the standard, a shaft connecting the levers, said shaft having a 90 finger piece at one end thereof and a head at the opposite end thereof, a printing drum rigid with the shaft, a series of independent printing surfaces mounted upon the periphery of the drum, a fork straddling the 95 drum and pivoted upon the shaft, the arms of the fork terminating in pointers which indicate which one of the printing surfaces is in operative position, a spring interposed between the head of the shaft and the fork for causing the fork to frictionally grip the 100 drum, inking means, and a handle on the arched end of the fork for swinging the printing drum toward the base plate.

5. A rotary stamping device, including a 105 base plate, a standard, a pair of levers pivotally mounted upon the standard, a shaft connecting the levers, a printing drum mounted upon the shaft and provided at one end thereof with an annular series of 110 rounded projections, a series of independent printing surfaces mounted upon the periphery of the drum, a fork straddling the drum and pivotally mounted upon the shaft, one of the arms of the fork terminating in a 115 resilient pointer adapted to co-operate with the rounded projections on the end of the drum to hold the drum and fork in an adjusted position, the drum being adapted to be rotated within the fork to bring any 120 selected one of the printing surfaces opposite the pointer, inking means, and a handle on the arched end of the fork for swinging the printing drum toward the base plate.

6. A rotary stamping device, including a 125 base plate, a standard, a pair of levers pivotally mounted upon the standard, a shaft connecting the levers, a printing drum mounted upon the shaft and provided at one end thereof with an annular series of round- 130

ed projections, a series of independent printing surfaces on the periphery of the drum, a fork straddling the printing drum and pivotally mounted upon the shaft, one of the arms of the fork terminating in a resilient pointer adapted to coöperate with the rounded projections on the end of the drum to lock the drum and fork in an adjusted position, the drum being adapted 10 to be rotated within the fork to bring any selected one of the printing surfaces opposite the pointer, a spring mounted upon the shaft for causing the arms of the fork to frictionally grip the ends of the drum, inking means, and a handle applied to the arched end of the fork for swinging the drum toward the base plate.

15 7. A rotary stamping device, including a

base plate, a printing drum having undercut grooves in the periphery thereof, correspondingly shaped clips fitted removably within the undercut grooves, blocks engaged by the clips and provided with printing surfaces, means for mounting the printing drum so that it can be moved toward and 20 away from the base plate and rotated to bring any one of the printing surfaces into operative position, and inking means.

In testimony whereof I have signed my name to this specification in the presence of 20 two subscribing witnesses.

CHARLES DIMECH.
